UNITED STATES PATENT OFFICE.

SAMUEL M. TRAPP AND MATILDA L. TRAPP, OF SEATTLE, WASHINGTON.

SYSTEM OF PROTECTING BANK-CHECKS.

SPECIFICATION forming part of Letters Patent No. 774,345, dated November 8, 1904.

Application filed January 11, 1904. Serial No. 188,634. (No specimens.)

To all whom it may concern:

Be it known that we, SAMUEL M. TRAPP and MATILDA L. TRAPP, citizens of the United States, residing at Seattle, in the county of 5 King and State of Washington, have invented certain new and useful Improvements in Systems of Protecting Bank-Checks, of which the following is a specification.

Our invention particularly relates to the protection of bank-checks, but is applicable to drafts, bills of exchange, or other like monetary instruments; and the object of our invention is to provide a simple, effective, and convenient means for safeguarding a drawer's 15 funds or a bank's liability from alterations of the amount or forging a depositor's name upon a check by unscrupulous persons.

A description of our system as applied to bank-checks will be a sufficient indication of 20 its application to other purposes.

In the accompanying drawings, illustrating the application of the invention, Figure 1 represents a fragmentary sheet upon which is marked a collection of numbers or other symbols, and Fig. 2 a bank-check whereon one of 25 such symbols is used.

According to our system duplicate sets or collections of numbers or other symbols, such as alphabetic letters, are provided and disposed in series or groups. One of each such sets is furnished to a depositor, while the other one is retained by the bank; but no two 30 depositors have similar sets of numbers. The groups of numbers of each set may be ar-

35 ranged consecutively, at random, or, in fact, in any desired way; but only such numbers as have the same initial digits, which we will for convenience designate as "characteristics," will be placed in the same group. Each group 40 characteristic indicates a predetermined value which is mutually understood by the holders of both copies of any one set and when marked upon a check notifies the paying-teller of the bank having the deposited funds of a drawer 45 that no amount of money shall be paid upon that particular check which exceeds the value assigned to that characteristic. For instance, the drawer of the check finds by referring to his list, such as Fig. 1, that the group of 50 numbers having "17" for its characteristic

digits indicates, say, two hundred dollars. So he selects any number shown in this group—for example, "1758"—and writes the amount upon the check, which is otherwise drawn in the usual way, and marks off the appropriated 55 number from his list. When the check is presented at the bank for payment, the teller upon consulting his book containing the depositor's duplicate list of numbers finds within the group having "17" for a characteristic the entire 60 number inscribed upon the check and immediately marks it off from his list and pays the check, provided the amount written upon the latter does not exceed the value assigned to the group having "17's" for its characteristic. 65 Again, suppose a check is presented to the bank for four hundred and ninety dollars and bearing the check-number of "8127." Then the teller by reference to the drawer's duplicate 70 list discovers this particular number appears 70 on the list uncancelled, but that the numbers within this group and bearing "81" for a characteristic are assigned no greater value than one hundred dollars each, and the teller upon inspection recognizing the signature to 75 be genuine is led to discover that the check had been fraudulently raised from forty-nine dollars and by refusing to pay the same saves the bank from loss, as under the common law 80 the drawer can only be charged with the original amount unless by carelessness the drawer facilitates the forging, when the loss falls upon him.

It is apparent with the use of our system 85 that the depositor is protected either from compulsion or under duress to write out a check for any great amount of money, as the value of the check is determined by the particular number selected irrespective of whatever else may appear on a check. Furthermore, the payment may be stopped altogether 90 by simply using the same number a second time, for, as aforementioned, the teller is supposed to cancel each number as it is utilized. It is also apparent that this system 95 may be used with the checks now in use and the several numbers of which may be inserted thereupon in such a manner as to appear to designate the number of the check rather than as value thereof. As a further precaution 100

the fact that no two depositors have similar lists of numbers and that no number is used twice by the same drawer and the several numbers of each being selected at pleasure 5 makes this system of protecting checks exceedingly reliable and at the same time so simple as to be readily understood.

Having described our invention, what we claim as new, and desire to secure by Letters 10 Patent, is—

The protective bank-check system consisting of duplicate lists of numbers, severally divided into groups each number of the re-

spective groups having a characteristic or initial digit or digits designating a predetermined 15 monetary value for each and every of said numbers in its respective group and the digits following said characteristics being used for identification only, substantially as described.

In testimony whereof we affix our signatures 20 in presence of two witnesses.
